MEDAL

Ira Milton Jones, Milwaukee, Wis., assignor to World
War I Overseas Flyers, Inc., Milwaukee, Wis.

Filed Apr. 19, 1971, Ser. No. 135,533

Term of patent 14 years

Int. Cl. D11—03

U.S. Cl. D29—19 R

The single figure is a front view of the medal embodying my new design.

The reverse side of the medal is plain and forms no part of the design.

The vertical and horizontal lines on the ribbon from which the medal per se is suspended denote the contrasting colors of the ribbon.

I claim:

The ornamental design for a medal, as shown and described.
